UNITED STATES PATENT OFFICE.

ERNEST K. HOOD, OF INDIANAPOLIS, INDIANA.

PUMP.

No. 910,539.

Specification of Letters Patent.

Patented Jan. 26, 1909.

Application filed March 19, 1906. Serial No. 306,769.

To all whom it may concern:

Be it known that I, ERNEST K. HOOD, a citizen of the United States of America, residing at Indianapolis, in the county of Marion and State of Indiana, post-office the same, have invented certain new and useful Improvements in Pumps, of which the following is a specification.

The type of pump I have improved consists of a head with a discharge opening and a shaft suspended in a well casing, and provided at intervals with spiral propellers. Between these impellers are placed retarding plates. The shaft is rotated rapidly, and this starts the water in a spiral upward path. The retarder plates arrest its spiral motion and throw the water upward so that the next propeller can catch it. All pumps of this type have, heretofore, been provided with retarders, either supported by the shafting or by the sides of the well casing.

The object of my invention is to provide retarders supported from the top of the well which can be readily removed; and to also provide a removable protecting shield, carried by the same means carrying the retarders, whereby the propellers cannot wear either the well casing or retarder carrying means.

Another object of my invention is to provide means for packing a pump of this type whereby there will be no back leakage of water.

My invention consists in the combination and arrangement of parts hereinafter described and claimed.

Figure 1 represents a cross-section of my pump. Fig. 2 represents a perspective view of one shield and set of retarders.

The numeral "1" represents a head consisting of a base plate, "2," a discharge section, "3," and a head yoke, "4". A driving shaft, "5" is carried by this yoke and head and has shafting, "6" coupled to it which extends into the well. Propellers "7" are carried by shaft "6" at desired intervals. Supporting bars "8" are secured to the pump head, and extend down into the well along the inner periphery thereof. These bars carry retarding blades "9" at desired inter-

vals, preferably curved in form and extending toward the center of the well. These may be located at any point between the propellers, but I find it best practice to locate them immediately below a propeller. A removable ring or annulus "10" is fastened to bars "8" in such position as to surround the propeller, thus preventing wear of the bars, "8" or the well casing. To insure a water joint between ring "10" and the well casing I provide a flexible packing strip or strips "11". These also take up inequalities in the casing, and tend to cushion any vibration in the shaft or propellers.

In operation the shafting, retarder cage and ring are all inserted in the well together. The pump is started and water is raised as heretofore described. Water forced from one propeller to another cannot return except through the propeller, and as this is rotating, it cannot drop through it.

Actual practice shows that the cushion packing strips reduce the wear between the propeller and ring "10" to a minimum, as any vibration is received on a cushioned surface. If rings "10" become worn, the pump can be pulled and these replaced.

I am aware of the fact that impellers have been made with a ring cast integral with them, and I propose to use this with my improvement. However, a plain impeller may be used.

I claim as my invention:

In a pump of the class described the combination of a head; a shaft extended into the well, one or more impellers carried thereby, supporting bars extending from the head down into the well and parallel with the shaft; a protecting shield secured to said bars for each impeller, a cushion or packing strip around said protecting shield and between the bars and retarder blades secured to said bars, substantially as and for the purpose set forth.

ERNEST K. HOOD.
